Horace Pettit.

UNITED STATES PATENT OFFICE.

WILLIAM R. HALL, OF PHILADELPHIA, PENNSYLVANIA.

MOLD FOR THE MANUFACTURE OF ARTIFICIAL TEETH.

SPECIFICATION forming part of Letters Patent No. 404,703, dated June 4, 1889.

Application filed October 29, 1888. Serial No. 289,431. (No model.)

To all whom it may concern:

Be it known that I, WILLIAM R. HALL, of the city of Philadelphia, and State of Pennsylvania, have invented a certain new and useful Improvement in Molds for the Manufacture of Artificial Teeth, of which the following is a full, clear, and exact description, reference being had to the accompanying drawings, forming part of this specification.

10 My invention has relation to molds for the manufacture of artificial teeth provided with stamped matrices which form linings to the tooth-concavity of the mold; and it consists in the elements and features hereinafter particularly described and claimed.

15 The object of my invention is to produce in a mold for the manufacture of artificial teeth a mold-shell having the exact form, shape, and delineation of the natural tooth, 20 which mold-shells I form by means of dies properly graved. The features and advantages of my invention are as hereinafter set forth.

25 In the accompanying drawings similar letters of reference refer to similar parts throughout.

Figure 1 represents the lower half of the mold-shells applied to a molding-frame in a convenient number or series. Fig. 2 represents the upper or corresponding half of the same. Fig. 3 is a perspective view of the molding-frame closed, as in the act of molding. Fig. 4 is a cross-sectional view of the mold in the lines xx of Fig. 1. Fig. 5 shows 30 the male section of the die for producing the molding-shell. Fig. 6 is a perspective view of a one-half section of the mold-shell separated from the molding-frame.

40 a' represent the half-sections of the mold-shells.

A represents the lower half of the molding-frame, to which the sections of the mold-shell a are applied.

45 A' represents the upper or corresponding half of the molding-frame.

D represents the die, presenting in relief the shape and conformity of the front of an artificial tooth desired to be produced, as a convenient and expeditious method of making the shells.

50 b is the backing-plate, provided with cavities corresponding in shape to the out-

ward form of the mold-shells $a a'$, into which the said shells $a a'$ are set or countersunk, as a convenient method of applying them to the 55 mold-frame $A A'$, which said plate b is screwed or otherwise fitted into the said frame. Pins $c c$ are provided on the ends of the frame $A A'$, which fit into the orifices c' and secure the upper and lower sections of the molding-frame in the proper position in the process of molding.

The shells $a a'$ are of thin sheet-nickel or other suitable material, and are given the proper conformity and shape of the face or the 65 back of the artificial tooth to be produced, as the case may be, by means of a die, such as shown in Fig. 5, or other suitable means. These sections $a a'$ are set or countersunk into the backing-plate b , provided with concavities, as described, shaped in conformity to the outer conformation of the respective shell-sections. The backing-plate b , provided with the said shell-sections $a a'$, is fitted into a suitable molding-frame, such as shown in 70 Figs. 1, 2, and 3, in such a position that the edges of the shell-sections shall be on a line with the inner surface $e' e'$ or $e e$ of the molding-frame $A A'$. In this way the surface of the edge of the half-section a will come into 75 exact conformity and juxtaposition with its mate a' , adjusted in the other half of the molding-frame, when the frames $A A'$ are adjusted together, as shown in Fig. 3. It will thus be seen that when the requisite 80 quantity of plastic composition is provided in the shell-sections and the section A' of the molding-frame is adjusted upon the section A the plastic composition will be given the shape of an artificial tooth of the combined forms 85 of the shells $a a'$. The molding-frames $A A'$ are preferably made of heavy brass or bronze, to withstand the wear and tear involved in the ordinary heating and molding process to 90 which they are thereupon subjected.

95 A particular feature of my invention is the shell-mold for the manufacture of artificial teeth, which does away with the necessity of cutting and shaping the cavities for molding the teeth with gravers, and produces a cheaper, 100 better, and more uniform mold than those heretofore used in the manufacture of artificial teeth.

Having thus described my invention, what

I claim, and desire to secure by Letters Patent, is—

In an artificial-tooth mold, the molding-frame A A', in combination with the mold-shells a a', the backing-plate b, in which the mold-shells are set, the frame provided with the pins c c, and the orifices c' c', substantially as hereinbefore set forth and described.

In witness whereof I have hereunto set my hand this 24th day of October, A. D. 1888.

WILLIAM R. HALL.

Witnesses:

CHARLES W. BOGER,
HORACE PETTIT.
